UNITED STATES PATENT OFFICE.

CLARENCE H. HOWARD, OF ST. LOUIS, MISSOURI.

RAILROAD MOTOR-CAR TRUCK.

No. 926,189.

Specification of Letters Patent.

Patented June 29, 1909.

Application filed March 6, 1909. Serial No. 481,705.

To all whom it may concern:

Be it known that I, CLARENCE H. HOWARD, a citizen of the United States, residing at St. Louis, in the State of Missouri, have 5 invented a new and useful Improvement in Railroad Motor-Car Trucks, of which the following is a specification.

My invention relates particularly to the side frames of a railroad motor-car truck 10 and to the means for connecting the motor-bed thereto, and is in the nature of a modification of my invention for which I have made application for Letters Patent of the United States, February 26, 1909, Serial 15 Number 480,130, for improvement in railroad motor-car trucks, and my invention has for its object to provide a strong, rigid, and durable truck-frame, and to increase the efficiency and stability of the truck by applying 20 the motive power longitudinally through the upper portion or compression members of the side frames and thereby enable the said frames to be made of greater depth with the same amount of material while 25 maintaining the normal height of the motor-bed from the railroad track.

The invention consists in features of novelty as hereinafter described and claimed, reference being had to the accompanying 30 drawing forming part of this specification, whereon,

Figure 1, is a top plan view of the side frames and connecting members of my improved motor-car truck; Fig. 2, a side elevation thereof; Fig. 3, a vertical transverse section to enlarged scale, through the motor-bed forming one of the said members, on line 3, 3, in Fig. 1, showing its connection with the corresponding side frame (seen in 35 side elevation broken away), and Fig. 4, a vertical longitudinal section through the end portion of the motor-bed at its junction and intersection with the side frame, on line 4, 4, in Fig. 1.

Like letters and numerals of reference 45 denote like parts in all the figures.

a represents the two opposite side frames of my improved motor-car truck which are connected together at and adjacent to the 50 rear side of the bolster *b* (indicated by dotted lines in Fig. 1) by the preferably channel-shaped transverse member or transom *c*, and at and adjacent to the front side of the bolster *b* by the motor-bed *d* which is used 55 in lieu of the ordinary transverse member

or transom on this side of the bolster, the transverse connecting members *c* and *d* being formed with suitable projections 1 for the usual chafing plates in engagement with corresponding plates on the bolster *b*, and 60 with the usual hanger brackets 2, while the side frames *a* are connected together at their front ends by the preferably channel-shaped transverse member *e*, all the said parts, namely, the side frames *a* and the transverse 65 connecting members *c*, *d*, and *e*, being preferably composed of cast steel integral throughout and having preferably, suitable corner gussets or reinforcing horizontal webs 3, 4, and 5, at the junctions of the said members 70 respectively, with the side frames *a*.

The motor-bed *d* on which the gasoline engine or other suitable motor is mounted and fixed in the usual well-known manner, is in the present case preferably, concave or 75 trough-shaped in cross section, of suitable width and depth, and extends lengthwise between and preferably, intersects the upper portion or compression members of the side frames *a*, the top of the motor-bed *d* being 80 preferably, flush with the top of the side frames *a*.

Across and preferably, integral with the motor-bed *d* at suitable intervals along the same, are formed a series of upright webs 85 or brackets 6 having respectively, a bearing 7 for the driving shaft of the motor (not shown), the bearings 7 being arranged in longitudinal alinement with each other transversely to the truck and having their 90 longitudinal center preferably in the horizontal plane of the upper portion or compression members of the side frames *a*.

By the above construction in which the motor-bed *d* is integral with, and forms a 95 part of the compression members of the side frames, deeper and stronger side frames can be used with the same amount of material, and by applying the motive power from the drive shaft of the motor longitudinally 100 through the compression members of the side frames as near as practicable to the railroad track, combined with the bracing of the side frames by their connecting transverse members integrally united therewith, 105 a strong, rigid, and durable structure is obtained and the efficiency and stability of the truck insured.

f are suitably shaped openings formed transversely through each side frame *a* for 110

receiving the equalizer-springs (not shown) within the body of the frame below its top member, whereby sufficient clearance is insured between the top of the frame *a* and the car-body, the top wall of each opening *f* having a spring-seat *8* preferably integral therewith.

What I claim as my invention and desire to secure by Letters Patent is:—

- 10 1. In a railroad motor-car truck, the combination with the side frames thereof, of the motor-bed adapted to connect the said frames together transversely to the truck, and integral therewith, substantially as described.
- 15 2. In a railroad motor-car truck, the combination with the side frames thereof, of the motor-bed, and a transom, adapted respectively, to connect the said frames together transversely to the truck and integral therewith, substantially as described.
- 20 3. In a railroad motor-car truck, the combination with the side frames thereof, of the motor-bed, and a front member, adapted respectively, to connect the said frames together transversely to the truck, and integral therewith, substantially as described.
- 25 4. In a railroad motor-car truck, the combination with the side frames thereof, of the motor-bed, a transom, and a front member, adapted respectively, to connect the said frames together transversely to the truck, and integral therewith, substantially as described.

truck, and integral therewith, substantially as described.

5. In a railroad motor-car truck, the combination with the side frames thereof, of the motor-bed adapted to form a part of the compression members of the said frames and integral therewith, substantially as described.

6. In a railroad motor-car truck, the combination with the side frames thereof, of the motor-bed adapted to intersect the compression members of the said frames and integral therewith, substantially as described.

40 7. In a railroad motor-car truck, the combination with the side frames thereof, of the motor-bed, and a transom, adapted respectively, to connect the said frames together transversely to the truck and integral therewith, the said bed intersecting the compression members of the said frames, substantially as described.

45 8. In a railroad motor-car truck, the combination with the side frames thereof, of the motor-bed adapted to connect the said frames together transversely to the truck and integral therewith, the said bed having corner gussets at its junctions with the said frames, substantially as described.

50 CLARENCE H. HOWARD.
